TOILET BOWL

Allen Priess, Hermann, Mo.

Application May 4, 1937, Serial No. 140,712

5 Claims. (Cl. 4—216)

The present invention relates to new and useful improvements in toilet bowls and has for its primary object to provide, in a manner as hereinafter set forth, novel valve controlled ventilating means for removing all odors when the toilet is in use.

Another very important object of the invention is to provide a novel construction and arrangement whereby the control valve will remain open while the toilet is in use and until after it has been flushed but which will then be automatically closed thereby preventing the withdrawal of air from the room when the toilet is not in use.

Other objects of the invention are to provide a ventilated toilet of the aforementioned character which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a vertical sectional view through the invention.

Figure 2 is a horizontal sectional view, taken substantially on the line 2—2 of Fig. 1, the seat cover and other parts being omitted.

Figure 3 is a fragmentary view in cross section through an upper portion of the bowl, taken substantially on the line 3—3 of Fig. 2.

Figure 4 is a detail view in horizontal section, taken substantially on the line 4—4 of Fig. 1.

Figure 5 is a detail view in elevation of the vertically movable member to which the seat and cover are connected.

Referring now to the drawings in detail, it will be seen that the reference numeral 1 designates generally a bowl having in its upper portion and extending entirely therearound a perforated water chamber or passage 2 for flushing said bowl. The water passage 2 is connected by a pipe 3 with a flush tank 4. Rising from the bottom of the flush tank 4 to a point above the highest level reached by the water therein is a tube 5, the purpose of which will be presently brought out.

The top of the bowl 1 includes a raised rear portion 6 having formed therein an air intake chamber 7 of substantially the cross sectional shape shown to advantage in Fig. 3 of the drawings. The chamber 7 communicates with the

bowl 1 and it will be observed that said chamber is located above the water passage 2. A vent pipe 8 communicates with the chamber 7 at the rear thereof and said vent pipe has interposed therein, adjacent the rear of the bowl 1, a control valve 9 of the butterfly type which is provided with an operating crank 10.

Pivotedly connected to the free end of the crank 10 and extending upwardly therefrom through the tube 5 into the upper portion of the flush tank 4 is a vertically movable rod 11 which terminates in a downturned upper end portion 12 having mounted thereon a float 13. The float 13 is adapted to be raised by the rising water in the tank 4 after the bowl 1 has been flushed. The rod 11 is operable in resilient guides 14 which are provided therefor in the tube 5, said guides being substantially in the shape of the numeral 3, as best seen in Fig. 4 of the drawings. The guides 14 are of suitable resilient wire and are formed, at an intermediate point, to provide a loop 15 through which the rod 11 passes.

Mounted on the rear portion 16 of the bowl 1 are upstanding guides 17 in which a transverse rod 18 is mounted for vertical movement. Connected to the rod 18 for swinging movement in a vertical plane is a seat 19 and a cover 20. Coil springs 21 yieldingly support the rear end of the seat 19 in elevated position on the raised rear portion 6 of the bowl 1. Resilient bumpers or stops 22 support the front end of the seat 19 on the comparatively low front portion 23 of the bowl 1.

Mounted on one end portion of the transverse, vertically movable rod 18 and extending rearwardly therefrom is an arm 24. The rod 11 extends slidably through the rear end portion of the arm 24 and has fixed thereon beneath said arm and for engagement thereby a collar 25 or the like.

It is thought that the operation of the invention will be readily apparent from a consideration of the foregoing. When the seat 19 is occupied the rear end thereof is depressed against the tension of the coil springs 21 thereby moving the rod 18, together with the arm 24 downwardly. Downward movement of the arm 24 lowers the rod 11 and opens the valve 9, a float 13 being submerged in the water in the flush tank 4. It will thus be seen that the vent pipe 8 will be opened and the draft therein will be amply sufficient to thoroughly ventilate the bowl 1. When the toilet is flushed and the occupant or user leaves the seat 19, said seat, together with the rod 18, the arm 24, etc., is again raised by the springs 21 but the

control valve 9 will remain open until after the flushing operation has been completed and the water in the tank 4 again reaches its normal level. When the water in the tank 4 thus reaches its normal level the rod 11 is raised by the float 13 for closing the valve 9. With the valve 9 closed withdrawal of air from the room in which the toilet is located through the vent pipe 8 will be prevented.

10 It is thought that the many advantages of a ventilated toilet constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:—

20 1. A toilet comprising a bowl, a flushing apparatus connected to said bowl, a ventilating means connected to the bowl and including a control valve, a seat for the bowl operatively connected to the valve for opening same, and means operatively connecting the flushing apparatus to the valve for closing same.

25 2. A toilet comprising a bowl, a flushing apparatus connected to said bowl, a ventilating means connected to the bowl, manually operable means for rendering said ventilating means operative, and means operatively connecting the flushing apparatus to the ventilating means for rendering said ventilating means inoperative.

30 3. A toilet comprising a bowl, a flushing apparatus connected to said bowl, a ventilating means

connected to the bowl and including a control valve, a depressible seat yieldingly mounted on the bowl, means operatively connecting the seat to the valve for opening said valve when said seat is occupied, and means operatively connecting the flushing apparatus to the valve for closing said valve after the bowl has been flushed.

4. A toilet comprising a bowl, a flushing apparatus connected to said bowl, a ventilating means connected to the bowl and including a control valve, a depressible seat yieldingly mounted on the bowl, means operatively connecting the seat to the valve for opening said valve when said seat is occupied, and means operatively connecting the flushing apparatus to the valve for closing said valve after the bowl has been flushed, the last named means including a tube extending upwardly in the flushing apparatus, a rod extending slidably through said tube and having one end connected to the valve, and a float on the other end of said rod.

5. A toilet comprising a bowl, a flush tank connected to said bowl, a ventilating pipe connected to the bowl, a control valve interposed in said ventilating pipe, a tube extending upwardly in the flush tank from the bottom thereof, a rod extending slidably through said tube and having one end connected to the valve, a float on the other end of the rod, said float and rod constituting means for closing the valve, and guides for the rod mounted in the tube, each guide being substantially in the shape of the numeral 3 and of resilient material and including a loop at an intermediate point for the passage of the rod.

ALLEN PRIESS. 35
